GENERATOR TERMINAL SHIELD

Frank G. Gardner and Conrad G. Merrill, Newark,
N. J., assignors to Breeze Corporations, Inc.,
Newark, N. J., a corporation of New Jersey

Application April 6, 1935, Serial No. 14,973

4 Claims. (Cl. 171—252)

This invention relates to shields for the terminals of electrical devices.

Where radio is used in close proximity to an internal combustion engine or under circumstances where current is flowing through an electrical system, interference with the radio equipment is experienced. This is caused by the emanation of electrical impulses from the devices or wires carrying the current. In order to avoid such interference it is necessary to surround the electrical conductors and the various electrical devices with conductive housings which will promptly dissipate such emanations to ground. In connection with the use of radio in the vicinity of an internal combustion engine, and particularly in aircraft practice, it is necessary to shield the entire ignition system, including its auxiliary units to avoid interference.

The object of this invention is to provide a simple, effective and easily installed radio shield for the terminal of an electrical unit, and particularly the terminal of the common form of generator used on aircraft.

A further object of the invention is to provide such a shield which may be applied without change in the structure or assembly of the generator, and which will provide means to co-operate with other shielding elements which shield the conductor leading to the generator.

Under normal conditions the casing of the generator proper is of metal and is grounded so that it is only necessary to shield the terminal of the generator completely to shield this unit. However, it is frequently desirable to use a condenser with the generator. Therefore, a further object of the invention is to provide a radio shield for the terminal of the generator with which shield a condenser may be used. A further object of the invention is to provide a condenser of such construction that it may be readily applied to the shield without change in the structure of the shield.

The invention consists of the construction, combination and arrangement of parts, as herein illustrated, described and claimed.

In the accompanying drawing is illustrated one form of embodiment of the invention, in which drawing similar reference characters designate corresponding parts, and in which letters are used to designate parts forming no part of this invention, and numerals are used to designate the parts forming the invention herein, and in which:

Figure 1 is a vertical section, partly in eleva-

tion, showing the application of the shield to the terminal of the generator; and,

Figure 2 is a vertical section, partly in elevation, showing the application of the condenser to the generator and shield.

Referring to the drawing, A designates the casing of a generator which is provided with the usual terminal B having a threaded binding post C. The post C is adapted to receive a metal contact tip D of the insulated conductor E.

Surrounding the terminal B is an open-ended tubular metallic shield 3 having an inturned flange 4 formed at the bottom thereof. The flange 4 is curved to conform to the contour of the generator A. The upper end of the tubular member 3 is formed with a screw-threaded neck 5 which is normally closed by a disc 6 resting on the neck 5, and the disc 6 is held securely in position by means of a coupling nut 7.

In order to hold the member 3 on the generator A, a composition or other washer 8 is disposed around the terminal B. The washer 8 is surmounted by a metal washer 9 and a nut 10 is applied on the post C to force the washers 8 and 9 against the flange 4, which in turn is forced against the generator A, thus holding the tubular member 3 rigidly in position on the generator A.

In the assembly of the device the nut 7 and the disc 6 are removed so that a socket wrench or other tool may be inserted through the open top of the member 3 to secure the nut 10 in position.

The contact tip D is then applied to the post C and a second nut 11 is applied to the post C to securely hold the contact member D.

The tubular member 3 is provided with a substantially tubular lateral extension 12 terminating in a threaded neck 13 adapted to receive the coupling nut G of a shielding conduit F. The conductor E extends through the extension 12 and the conduit F.

Referring to Figure 2, 14 designates a condenser, the metal casing of which forms one contact and the opposite contact is in the form of a coil spring 15. The condenser 14 is formed with an annular bead 16. When it is desired to use the condenser 14, the nut 7 is removed and the disc 6 is discarded. The condenser 14 is of such size that it may be entered in the upper end of the tubular member 3 and the bead 16 will rest on the upper edge of the neck 5. The nut 7 is then applied over the condenser 14 and tightened on the neck 5 to hold the condenser securely in position. The spring 15 is compressed against

the post C to make contact therewith, and the casing of the condenser 14 is grounded through the tubular member 3 and the generator A.

From the foregoing it will be seen that with 5 the construction shown in Figure 1 a complete shield is provided for the terminal of the generator. As shown in Figure 2 the shield readily lends itself to the use therewith of a condenser and the condenser is entirely shielded.

10 Having thus fully described the invention, what is claimed as new and desired to be secured by Letters Patent is:

1. In combination with a generator terminal and a radio shield therefor, a tubular condenser 15 formed with an annular bead and a spring contact, said spring contact being shielded by the terminal shielding means.

2. A radio shield for the terminal of a generator comprising an open-ended, substantially 20 tubular member surrounding the terminal, an internal flange formed on the lower edge of the member and in contact with the generator, a washer surrounding the terminal and bearing against the flange, a nut on the terminal to hold 25 the shield in position, a disc disposed on the upper end of the open-ended member, a remov-

able coupling nut to hold the disc in position and a lateral extension on the tubular member.

3. A radio shield for the terminal of a generator comprising a tubular member surrounding the terminal and extending past the upper end 5 thereof, means carried by the terminal to hold the tubular member in position, a condenser disposed in the upper end of the tubular member, said condenser having a spring contact in contact with the terminal, an annular bead on the condenser resting on the upper end of the tubular member, means to hold the condenser in position 10 and a lateral extension on the tubular member to admit the insertion of a conductor.

4. In combination with a generator terminal 15 and a radio shield therefor, a tubular condenser formed with an annular bead, said condenser having a metal casing grounded to the shield and a spring insulated from the casing, said casing forming one contact of the condenser and said 20 spring forming a second contact, the ungrounded portion of the condenser being shielded by the terminal shielding means.
